STREET SWEEPER BRUSH AND MOUNTING

Ronald Clement Evans, Elgin, Ill., assignor to
Elgin Sweeper Company, Elgin, Ill., a corpora-
tion of Illinois

Application June 30, 1938, Serial No. 216,740

6 Claims. (Cl. 15—80)

This invention relates to a street sweeping apparatus, and more particularly to a novel caterpillar sweeper brush and brush assembly.

Many forms of street sweeping apparatus have been employed in the past for sweeping streets and other surfaces to be swept. The different forms of sweeping apparatus may be roughly classified as caterpillar brush sweepers, rotary brush sweepers, and combined rotary brush conveyor sweepers. Caterpillar brush sweepers have not met with the same degree of success as the other two types of sweepers. There may be many explanations for this, but the principal one appears to lie in the fact that an efficient caterpillar brush and brush assembly has not as yet been designed which could be manufactured at a reasonable cost and be rugged and reliable in use.

It is an object of the present invention to provide a novel sweeper brush and brush assembly which is economical to manufacture, which is rugged and reliable in use, and which is extremely efficient in operation.

Another object of this invention is to provide a novel form of caterpillar brush and caterpillar brush assembly.

A further object of this invention is to provide a novel means for securing brush bristles and fibres to a pair of endless articulated chains.

Another and further object of this invention is to provide a novel caterpillar sweeper brush assembly made up of a plurality of individual brush units which may be quickly and easily removed and mounted in the assembly.

Another and still further object of this invention is to provide a novel means for adjusting the relative position of the caterpillar brush and for tensioning the brush and brush assembly.

A still further object of this invention is to provide a novel caterpillar sweeper brush assembly made up of a plurality of individual brush units each of which is comprised of a plurality of bristle holders which may be filled with bristles before being assembled into a brush unit.

The novel features which I believe to be characteristic of my invention are set forth and described with particularity in the appended claims. My invention itself, however, both as to its construction and organization, together with further objects and advantages thereof, may best be understood by reference to the following description taken together with the accompanying drawings, in which:

Figure 1 is a side elevational view of a street sweeping apparatus employing a caterpillar brush

embodimenting the principles of the present invention;

Figure 2 is an enlarged fragmentary elevational view illustrating the lower end of the caterpillar brush assembly;

Figure 3 is an enlarged fragmentary cross-sectional end view of a pair of brush units;

Figure 4 is an enlarged fragmentary front view, partly in cross-section, of the brush units shown in Figure 3 and taken at right angles to said figure;

Figure 5 is a fragmentary cross-sectional elevational front view of a brush unit and the sprocket and shaft upon which it is carried, approximately half of the width of the brush being shown;

Figure 6 is a cross-sectional view along the line 6—6 of Figure 5 and looking in the direction of the arrows, with the bristles omitted;

Figure 7 is an isometric, exploded view of a modified form of brush head;

Figure 8 is an enlarged cross-sectional end view of a brush unit embodying the type of head shown in Figure 7;

Figure 9 is an enlarged fragmentary front view, partly in cross-section, of the type of brush unit shown in Figure 8, showing the manner in which the outwardly diverging end bristles cooperate with a portion of the sweeper;

Figure 10 is a cross-sectional view of a modified form of brush head;

Figure 11 is a side elevational view of a modified form of street sweeping apparatus employing my novel caterpillar brush;

Figure 12 is a skeleton view taken along the line 12—12 of Figure 1 showing the tensioning mechanism illustrated therein, but with the other elements of the apparatus eliminated from this view for the purpose of clarity; and

Figure 13 is an enlarged fragmentary elevational view showing the adjusting means of the tensioning mechanism shown in Figure 12.

The sweeping apparatus illustrated in Figure 1 of the drawings is a street sweeper of the caterpillar brush type similar to that shown in my copending application Serial No. 207,446, filed May 12, 1938, and assigned to the same assignees, and of which this application is a continuation-in-part. The sweeping elements of this apparatus, together with their associated elements, are mounted on a motor driven vehicle 10, the principal component parts of the complete apparatus being the caterpillar brush assembly 11, a dirt and debris storage hopper 12, and a chassis 13 having a rear-mounted motor 14 thereon (the

motor being diagrammatically indicated by showing the customary hood enclosing the same). The chassis 13 includes a pair of front wheels 15 mounted on a fixed axle (not shown) and a pair of rear wheels 16 which are preferably mounted closely together on a pivoted steering assembly 17. Steering assembly 17 is connected through any suitable connecting mechanism to a steering wheel disposed in the driver's compartment or cab 18.

To enhance the general appearance of the vehicle 10 and to protect the sweeping apparatus from the elements, a body 19 is provided which forms a continuation of the cab 18 and which may be given any shape which will further enhance the general appearance of the vehicle. In the upper forward wall of the body 19 a relatively large transverse opening (not shown) is provided to permit access to the upper portion of the caterpillar brush assembly 11.

The dirt and debris collecting hopper 12 is situated at the extreme forward end of the vehicle 10 and communicates directly with the upper portion of the brush assembly 11. Hopper 12 is designed to receive dirt and debris carried upwardly thereto by the sweeping apparatus and to store the same until it is desired to empty the hopper 12.

The caterpillar brush assembly 11 includes, in general, a caterpillar brush 20 and a caterpillar brush housing 21. One form of brush housing which has been found to be highly satisfactory in practice is shown in detail and claimed in my above mentioned application Serial No. 207,446. In general, this comprises suitable housing members including side walls, a sloping front wall and a rear wall 22. In order to permit ready accessibility to the caterpillar brush 20, the rear wall 22 includes a pivotally mounted panel 23 (shown in Figure 2) which preferably extends over a major portion of the rear wall 22.

The caterpillar brush assembly also includes pairs of sprocket wheels 24, 25 and 26, over which ride two endless articulated caterpillar brush chains 27 forming part of the caterpillar brush 20. These sprocket wheels are preferably mounted as disclosed in detail in my above-mentioned copending application. To adjust the tension in the endless chains 27 and to provide a means of taking up wear in the chains themselves, an adjusting means is provided as shown in Figures 1, 12 and 13. The adjusting means comprises a shaft 28 extending across the brush assembly 11 between the upper and lower reaches of the caterpillar brush 20. The shaft 28 carries a pair of arms 29, on the ends of which are journaled a pair of idlers 30 which engage the upper reaches of the caterpillar chains 27 from underneath. The ends of the shaft 28 project through the sides of the brush housing 21 in which they are journaled and are provided with arms 31 keyed thereto. The ends of the arms 31 are engaged by tensioning bolts 32 mounted on the sides of the brush housing and provided with lock nuts 33. Thus, adjustment of the bolts 32 will rock the shaft 28 and move the idlers 31 in such a manner as to vary the tension in the caterpillar brush chains 27 and to compensate for wear therein.

The caterpillar brush 20 is built on the two endless chains 27 already referred to. The chains 27 are similar to ordinary roller chains but, in the particular form of the invention shown in Figures 2 to 6, the side plates 34 of every fourth link are of special shape for the purpose of car-

rying a pair of brush units 35. The special side plates 34 are of angle form, similar to short pieces of angle iron, one flange of each side plate forming a part of the chain and the other side 5 forming a part of a bracket 34-36, to which a pair of brush heads 35 are secured. The remainder of this bracket 34-36 is formed of a block 36 riveted to the bracket portion of the side plate 34 and having a rectangular portion 37 which lies within the angle of the side plate 34 alongside of the chain 27 and to which the brush heads 35 are bolted. Since the side plates 34 are arranged in pairs, the rectangular blocks 37 are also arranged in pairs, one on each side of the 10 chain 27, so as to transmit to the chain 27 the loads from the brush heads 35 in a symmetrical manner.

Each brush head 35 comprises a channel-shaped back 38 into which the brush fibres 39- 20 which may be of bamboo, for example—are clamped by means of a clamping bar or tube 40. The clamping bar or tube 40 is provided with several studs 41 welded to it and extending through the top of the brush back 38, and nuts 25 42 are threaded onto the projecting ends of the studs 41 for pulling the clamping tube 40 into the channel-shaped back 38, thus securing the brush fibres 39. The brush fibres 39, being tightly wedged into the channel 38 along with the 30 clamping tube 40, exert considerable pressure tending to spread the sides of the channel 38 apart. To assist in strengthening the channel 38 against this pressure, corrugations 38a extending around the channel are provided at intervals and the edges of the channel are strengthened by being formed into outwardly directed flanges 38b.

As shown in Figure 3, the channel 38 may be made relatively deep and the clamping bar 40 may have flat sides so as to strongly support the fibres 39. The ends of the brush channels 38 and the clamping bar 40 may be bent up slightly so as to cause the fibres near the ends of the brush to flare out against the side of the brush housing 21 as shown in Figure 5. This feature has been found to be highly desirable and extremely beneficial due to the fact that the brush fibres 39 at the outer ends of the brush units 35 directly engage the inner surface of the caterpillar brush housing 21. This feature of extending the brush fibres 39 at the extreme ends of the brush units 35 outwardly at a slight angle so as to engage the inner surface of the caterpillar brush housing 21 assures the absence of any dirt and debris leakage between the ends of the brush units 35 and housing 21.

At each side of each chain 27, each channel-shaped brush back 38 has one leg 43 of an angle bracket 43-44 notched over it and welded to it. The other leg 44 of each angle bracket 43-44 lies parallel to the brush back 38 and against one face of the brush fastening blocks 37 carried on each side of the chain 27. Thus, each of the blocks 37 on each side of the chain 27 has a leg 60 44 of a brush back bracket 43-44 on each side of it, and the two brackets 43-44 are removably secured to the block 37 by a bolt 45. Thus the brush heads 35 are secured to the chains 27 in pairs.

Besides being secured in pairs to the chains 27, the brush heads 35 are further secured together in pairs by end brackets 46-47 and center brackets 48-49. The end and center brackets are similar to the brackets 43-44 by which the brush heads are secured to the chains 27, but the legs

46 and 48 welded to the brush backs 38 are longer so that the other legs 47 and 49 of the brackets on one brush back lie flat against the corresponding legs of the brackets on the other brush back of a pair and can be secured together by bolts 50—51. The legs 48 of the center brackets are notched over and welded to the brush backs 38 in the same way as the legs 43 of the brackets near the chains, but the legs 46 of the end brackets, instead of being notched over the brush backs 38, are welded across their ends, as shown in Figure 6, to close them and to support the brush fibres 39 at the ends of the brush. The end brackets 46—47, as well as the center brackets 48—49 and the brackets 43—44 near the chains, also serve to reinforce the brush backs or channels 38 and assist the corrugations 38a in strengthening them against being spread open by the pressure of the brush fibres 39 and clamping bar 40.

From the above description, it will readily be observed that each pair of caterpillar brush units 35 may be readily and quickly removed and replaced. In other words, each pair of brush units 35 is separately removable as a subassembly from the entire brush assembly 20. As has previously been pointed out, the caterpillar brush housing 21 is provided with a pivotally mounted lower end panel 23, as shown in Figure 2, which may be raised to afford ready and quick access to the caterpillar brush units 35. By raising the closure panel 23, a service man can readily reach the pair of brush units 35 directly opposite, remove the bolts 45, and remove the pair of brush units secured thereby to the caterpillar brush chains 27. After the pair of brush units 35 has been removed from the caterpillar brush assembly 20, the two units may be separated and repaired or the brush fibres 39 lifted out and replaced.

Access to the individual brush units 35 may also be had by removing the cover 52 on a relatively large opening in the upper portion of the body 19.

A modified form of caterpillar brush is illustrated in Figures 7, 8 and 9. This particular embodiment of the modified form of the invention comprises a pair of caterpillar brush chains similar to the chain 27 shown in Figures 2 and 3 but having links approximately twice as long, and with every other link comprising special angle side members to which a brush unit is secured. As shown in Figure 8, the special side members 59 are provided with flanges 60 to which is riveted a channel-shaped brush head plate or box 55 forming part of a brush unit 53. Each brush unit 53 comprises the channel-shaped brush head plate or box 55, an intermediate grooved plate 56, a pair of fibre supporting or clamping bars 57, and a mass of brush fibre 58 clamped between the bars 57 and the grooved plate 56. While the brush head plate 55 is permanently secured to the brush chains, the remainder of the brush head, comprising the grooved plate 56, the clamping bars 57 and the brush fibre 58, may be removed as a unit. By providing fibre clamping and supporting members which may be individually removed, it will readily be understood that an extremely advantageous result is obtained, since it is not then necessary to remove the entire caterpillar brush assembly from the vehicle in order to repair or replace portions of the brush.

The particular means illustrated in the drawings for achieving this desired result will now be described. The intermediate grooved plate 56 of the brush unit 53 is provided with two longitudinally extending grooves 62 which are substantially semicircular in cross-sectional config-

uration. A series of tubes 63 are welded to the top of the intermediate plate member 56 and are of such a length as to slide freely between the side walls 64 of the channel member 55. The extent to which the intermediate plate member 56 extends into the channel of the channel member 55 is determined by the edge flanges 65 of the intermediate plate member 56 which engage the outer edges of the side walls 64 of the channel member 55. Apertures 66 are provided in the side walls 64 opposite the tubes 63 of the intermediate plate member 56 to permit bolts 67 to pass through the side walls 64 and through the tubes 63. The bolts 67 are detachably secured and held in place by nuts 68 which may be screwed onto the threaded ends 69 of the bolts 67.

The fibre supporting and clamping bars 57 are provided along their length with a plurality of threaded studs 70. These threaded studs 70 may be butt-welded or otherwise suitably secured to bars 57. The ends of the bars 57 are bent slightly upwards as at 71 for a reason which will presently appear. The base of channel plate 55 is apertured as at 72 opposite the ends of the threaded studs 70 to accommodate variations in the length of these studs. The intermediate plate 56 is apertured also, as at 73, for the reception of threaded studs 70. Nuts 74 are provided for threaded engagement with studs 70, it being understood that these nuts 74 tightly secure the fibre supporting and clamping bars 57 to the intermediate plate 56.

As may be seen best in Figure 9 of the drawings, the intermediate plate 56 is terminated so as to snugly fit within the end walls 75 of the channel-shaped head plate or box 55. It will also be observed that the end of the intermediate plate 56 is turned up slightly as at 76 in the same manner as the ends 71 of the supporting and clamping bars 57 were turned up.

The brush fibres 58 are thickly grouped together and hung over each fibre supporting and clamping bar 57, as shown in Figure 8 of the drawings. Note should be taken that the relative spacing of the grooves 62 in the intermediate plate 56 is such that the lower ends of the brush fibres 58 overlap as at 77. It should be further noted that the grooved portions 62 of the intermediate plate 56 are shaped to intimately seat the inner intermediate portion of the brush fibres 58.

From an examination of Figure 9, it will be observed that the brush fibres 58 at the extreme ends of the brush unit 53 are caused to extend slightly outwardly at an angle due to the slightly upwardly bent ends 71 and 76 of rods 57 and intermediate plate 58 respectively. This feature has been found to be highly desirable and extremely beneficial, as pointed out above in connection with the same feature in the form of the invention shown in Figures 2 to 6.

From the above description, it will be observed that the caterpillar brush unit 53, with the exception of the channel plate 55, may be readily and quickly removed and replaced. In other words, each individual brush unit 53 is separately and individually removable from the brush assembly for repair in a manner similar to that discussed above in connection with the form of brush illustrated in Figures 2 to 6.

In Figure 10 of the drawings, I have illustrated a modified form of brush unit which includes a wooden brush head 78 in place of the channel-shaped head 55 previously described. The brush head 78 is provided with longitudinally disposed

recesses 79 which are somewhat deeper than the grooves 62 of the intermediate plate 56 of the embodiment of the invention shown in Figures 7, 8 and 9. Brush fibre supporting and clamping bars 80 are provided which are similar in shape to the clamping bars 57 with the exception that the threaded studs thereon are made sufficiently long to extend completely through the head 78 and through the fastening flange 82 of link 83 of the endless chain. The fastening flanges 82 of the links 83 are somewhat larger than the fastening flanges 60, previously described.

Besides being adapted for use in the type of sweeper shown in Figure 1, the several forms of caterpillar brush described above may be used in the type of sweeper shown in Figure 11. This sweeper comprises the caterpillar brush 91, a dirt and debris storage hopper 92, and a chassis 93 having a forwardly mounted motor 94 thereon (the motor being diagrammatically illustrated by showing the customary hood enclosing the same). The chassis 93 includes a pair of rear wheels 95 mounted on a fixed axle (not shown) and a pair of front wheels 96 mounted closely together on a pivoted steering assembly 97. Steering assembly 97 is connected through any suitable connecting mechanism to a steering wheel 98. In this form of sweeping mechanism, the caterpillar brush 91 moves in the direction indicated by the adjacent arrow, and its linear speed is substantially greater than the forward speed of the vehicle. It will be seen, therefore, that the brush 91 sweeps in the reverse direction as compared to the brush in the sweeping mechanism shown in Figure 1.

While I have shown particular embodiments of my invention, it will of course be understood that I do not wish to be limited thereto, since many modifications may be made; and I therefore contemplate by the appended claims to cover all such modifications as may come within the true spirit and scope of my invention.

I claim as my invention:

1. A caterpillar brush for sweeping apparatus comprising a pair of endless flexible members, a plurality of brush units having attaching plates permanently secured thereto, a plurality of additional plates detachably secured to said first plates, a plurality of brush fibre supporting and clamping rods detachably secured to one of said groups of plates, and independent means for securing said rods to one of said groups of plates and for securing said plates together.

2. A caterpillar brush for sweeping apparatus comprising a pair of endless flexible members, a plurality of channel members permanently secured to said flexible members with their channels opening outwardly therefrom, a plurality of plates each having at least one longitudinal groove therein, a plurality of transversely disposed tubes secured to the backs of each of said plates, said plates being arranged to close the open faces

of said channel members with said tubes disposed within the channels of said channel members, and removable rods extending through said tubes and the side walls of said channel members for supporting and securing said plates to said channel members, and brush fibre supporting and clamping members disposed on the outer side of said plates and detachably secured to said plates for holding a multitude of brush fibres in firm engagement with the outer face of said plates.

3. A brush head for mounting brush fibres comprising a base member, a second member detachably secured to said base member, a brush fibre supporting member detachably secured to said second member, said second member having at least one longitudinally disposed groove therein for receiving and seating the folded ends of a multitude of brush fibres, and means for securing said supporting member to said second member independently of said base member.

4. A brush head for mounting brush fibres comprising a base member, a second member detachably secured to said base member, a brush fibre supporting member detachably secured to said second member, said second member having at least one longitudinally disposed groove therein for receiving and seating the folded ends of a multitude of brush fibres, said brush fibre supporting member being arranged to hold the folded ends of the brush fibres in the groove of said second member, and means for securing said supporting member to said second member independently of said base member.

5. In a caterpillar brush, a brush unit comprising a pressed metal channel having substantially parallel sides, a bar lying in the channel, means for forcing said bar into said channel, and U-shaped brush fibres having the bights thereof extending around said bar and clamped thereby in said channel, the edges of said channel being flanged outwardly and said channel having widely spaced, narrow corrugations extending there-around from one edge thereof to the other.

6. In a caterpillar brush including flexible traveling members, parallel pairs of brush units carried transversely thereby, each pair comprising two bristle-carrying portions channeled outwardly and connected in the direction of the length of the flexible members to each other in spaced relation and so that the bristles of the portion of each pair overlap, each portion having secured in the channel thereof brush bristles, each of said pair of channel portions being held on the flexible members solely by common fastening means extending and detachable in the direction of the length of said flexible members so that removal of said fastening means results in the detachment of the pair of portions from the flexible members.

RONALD CLEMENT EVANS.
